(57) **CLAIM**

The ornamental design for a hat shaping hair accessory as shown and described.

DESCRIPTION

FIG. 1 is a bottom perspective view of a hat shaping hair accessory showing my new design;

FIG. 2 is an enlarged partial view of a portion labelled 2 in FIG. 1;

FIG. 3 is an enlarged partial view of a portion labelled 3 in FIG. 1;

FIG. 4 is an enlarged partial view of a portion labelled 4 in FIG. 1;

FIG. 5 is an enlarged partial view of a portion labelled 5 in FIG. 1;

FIG. 6 is a front elevation view of FIG. 1;

FIG. 7 is an enlarged partial view of a portion labelled 7 in FIG. 6;

FIG. 8 is an enlarged partial view of a portion labelled 8 in FIG. 6;

FIG. 9 is an enlarged partial view of a portion labelled 9 in FIG. 6;

FIG. 10 is a rear elevation view of FIG. 1;

FIG. 11 is an enlarged partial view of a portion labelled 11 in FIG. 10;

FIG. 12 is an enlarged partial view of a portion labelled 12 in FIG. 10;

FIG. 13 is an enlarged partial view of a portion labelled 13 in FIG. 10;

FIG. 14 is a top plan view of FIG. 1;

FIG. 15 is a bottom plan view thereof;

FIG. 16 is an enlarged partial view of a portion labelled 16 in FIG. 15;

FIG. 17 is a right side elevation view of FIG. 1; and,

FIG. 18 is a left side elevation view thereof.

The dash-dash broken lines in the figures show portions of the hat shaping hair accessory that form no part of the claimed design. The dash-dot-dot broken lines depict bounds of the portions included in the partial enlarged views and form no part of the claimed design.
